UNITED STATES PATENT OFFICE.

WILLIAM C. ALBERS, OF NEW YORK, N. Y., ASSIGNOR OF THREE-FOURTHS TO ADOLPH W. HILLE, OF DENVER, COLORADO.

HOLLOW-SCREW ELEVATOR.

1,098,420.

Specification of Letters Patent.

Patented June 2, 1914.

Application filed April 25, 1913. Serial No. 763,499.

To all whom it may concern:

Be it known that I, WILLIAM C. ALBERS, a citizen of the United States, residing in New York city, in the county of New York and State of New York, have invented certain new and useful Improvements in Hollow-Screw Elevators, of which the following is a specification.

My invention enables the construction of cheap, durable and strong hollow-screw elevators for liquids and granular substances, which will lift the greatest quantity possible with given dimensions and in which the screw is so formed that it is impossible for air-traps to be formed, which impair the efficiency and restrict the duty of known types of such elevators.

The principal novel features of my elevator are as follows:

1. The form of the helix, which is radially inclined so that at all points it ascends from the envelop to the axis, so that the incipient screw adjacent to the axis is everywhere ascending and air traps are physically impossible.

2. The mode of building the envelop or tube, which is made of exactly similar helical plates rolled or pressed with a slight axial taper and a leading, radially-inclined flange. The tube is spiral-riveted and has a spiral, lapped tapered joint formed by slipping the following edge of one spire over the leading edge of the preceding one; and an inward stub screw or screw-flange formed 35 of the plate-flanges for connection with the helix, and similarly inclined.

3. The mode of connecting the helix and the axle.

4. The mode of joining the helix and envelop.

In the drawings, Figure 1 is a side view partly in section and Fig. 2 an axial section showing the preferred detail of the axle.

In the practice of my invention, I set my elevator E at a suitable angle, preferably fifty to seventy degrees with the horizontal, rotatably mount it on a suitable foundation, 1, and thrust bearing 2, illustrated as a ball-bearing, and provide a suitable head-frame 3 and head-bearing 4, and drive mechanism 5, which may be a frictional or toothed gear train connected with a source of power; and a flume or conduit 6 to convey the pumped water to its place of use. Both ends of 55 the elevator are open and its lower end is

submerged. The envelop or tube 7 is made of exactly similar plates, rolled or pressed into segments of a helix and with a slight axial taper and a leading flange 7^a, radially inclined at an angle slightly greater than the obtuse setting angle of the elevator; and suitably punched or drilled for riveting. The spiral joint is formed by slipping the following edges of spirals over the flanged edges of the preceding ones, so that the spiral joint is slightly tapered and the plate-flanges 7^a form a continuous radially upwardly inclined stub-screw or helical flange 7^b upon the inner surface of the tube.

The axial joints are riveted single butts with single butt-plates, inside the tube. The helix 8 is formed of exactly similar plates, rolled or pressed into segments of a radially-inclined helix, like the upper helical surface of a V-thread screw, the acute angle of radial inclination with the axis being slightly less than the acute setting angle of the elevator and being the complement of the plate-flange angle, so that when the elevator is assembled the helix 8 will fit the stub screw or helical flange 7^b. The joints of the helix are single butts with the butt-plates beneath it, and all similar. The axle 9 carries the head and foot bearings, a head collar 9^a and a jack screw thread 9^b interior to the foot bearing. The helix may be flanged and riveted to the axle, but I prefer the construction illustrated in Fig. 2 which shows in the axle, an incised, right-angled thread 9^c with lower and upper surfaces respectively parallel and perpendicular to the radial inclination of the helix. When the elevator is assembled, the inner edge of the helix 8 fits the axle thread 9^c, the collar 9^a confines the helix and a jack-nut, 9^d, on the jack-thread 9^b draws against a spider or transverse beams 7^e built on the tube 7, and pulls the helix 8 into close contact with the stub screw 7^b; and makes tight joints between the helix and the axle and tube.

I provide an outstanding lip or delivery-flange 7^f around the delivery end of the tube 7 to deliver the water into the flume 6 and on the dry side thereof the drive mechanism 5, preferably a worm gear 5^a on the tube 7 and a worm 5^b suitably mounted on the head frame 3 and connecting the elevator with a suitable motor. The worm gearing prevents the elevator from backing; and if I use other forms of gearing I retain the elevator, when

no power is supplied, by a pawl engaging the tube 7. On long elevators, I provide one or more intermediate bearings 10, consisting in a suitable cylindrical tread 7^a, preferably of channel section, on the tube 10^a, and a corresponding cylindrical rail 10^b supported by a suitable frame 10^c.

I increase the strength of my tubes as beams by axial trusses 11, preferably formed of a strut ring 11^a and tie-rods 11^b attached to the tube 7 adjacent to and extending between supports, tightened by turnbuckles 11^c, or otherwise, and bearing on the strut-rings, 11^a, which prevent the local thrusts 15 of the struts from deforming the tube. The strut-rings are preferably formed of a pair of matching, flanged, conical plates 11^d, riveted by their flanges to the tube 7 and riveted together at their apex.

20 The operation of my elevator when lifting water is as follows: Its lower end is submerged to any convenient depth and the submergence can vary to any extent without interfering with its operation; and it is rotated clockwise if its screw be right-handed, anti-clockwise if it be left-handed; and such rotation will lift water with no possibility of the formation of air-traps because the helix 8 is everywhere upwardly inclined, 25 and air in, or liberated from the water in the tube, will move against the under side of the helix, toward the axle and the adjacent part of the helix, which forms a continuously ascending helix, with no descending 30 limbs whatever in which air traps might form. This peculiarity is the essence of my invention. It will be observed that adjacent to the tube the helix has descending helical elements on its low side; but its radial inclination is such that from any point its 35 surface ascends radially toward the axle, that as the axle is approached the dip of the helical elements on the low side decreases and vanishes; and the helix ascends radially 40 in every part and helically adjacent to the axle furnishes a free outlet for air. The axle 9 and helix 8 may be detached and removed from the tube 7 by unscrewing the jack nut 9^d from the axle and the helix from 45 the tube, repaired in the open, and replaced.

Having thus described my invention, I claim:

1. A hollow-screw elevator adapted to be set with its axis inclined at a determined angle comprising a revoluble inclined tube and a helix in and attached to said tube and radially inclined thereto at an obtuse angle which exceeds the obtuse setting angle of the elevator with the horizontal.
2. A hollow screw elevator adapted to be set with its axis inclined at a determined angle comprising a revoluble inclined tube, and therein an axle and a helix connecting said tube and axle and radially inclined

thereto at an obtuse angle which exceeds the 65 obtuse setting angle of the elevator with the horizontal.

3. A hollow screw water elevator adapted to be set with its axis inclined at a determined angle and comprising a revoluble 70 tube, an axle extending through and a helix within and radially inclined to said tube and connected with it and said axle, the edge of said helix adjacent to said tube undulating toward and from an assumed horizontal 75 datum plane and the edge thereof adjacent to the axle everywhere ascending relatively to such plane.

4. A hollow screw elevator comprising a revoluble, inclined tube, a stub screw on the 80 inside of said tube and within it an axle, a helix connected with said axle and means to traverse the axle and helix axially in the tube and to strain said axle against said helix and said helix against said stub screw. 85

5. A hollow screw elevator comprising a revoluble, inclined tube, a stub screw on the inside of said tube and within it an axle, a thread in said axle, and a helix fitting said axle-thread and bearing on said stub screw, 90 and means to traverse the axle and helix axially in the tube and to strain said axle against said helix and said helix against said stub screw.

6. A hollow screw elevator comprising a 95 revoluble, inclined tube, a plurality of similar helical plates assembled in said tube, leading flanges on said plates radially inclined thereto at an obtuse angle exceeding the obtuse setting angle of the tube and 100 forming an interior screw-flange on said tube, and a helix radially inclined at a similar angle.

7. A hollow screw elevator comprising a revoluble inclined tube, a plurality of similar helical plates assembled in said tube, leading flanges on said plates radially inclined thereto at an obtuse angle exceeding the obtuse setting angle of the elevator with the horizontal, said plates being formed with 105 a slight taper and adapted to be assembled with a helical riveted lapped joint formed by lapping the following edges of plates over the leading flanged edges of adjacent plates, and a helix radially inclined at the 110 same radial angle as and in contact with the flanges of the tube-plates.

8. A hollow screw elevator comprising a revoluble inclined tube, a helix in said tube, supports for said tube, a strut ring intermediate between said supports, and a series of longitudinal stiffening trusses comprising oppositely inclined tie rods connected with said tube adjacent to and extending between said supports and connected with said 120 strut ring.

9. A hollow screw elevator comprising a revoluble, inclined tube, a helix in said tube,

three or more supports for said tube, a strut ring intermediate between every two supports, and a series of longitudinal stiffening trusses comprising oppositely inclined tension rods connected with said tube adjacent to each support and extending between adjacent supports and connected with the intermediate strut ring.

10. A hollow screw elevator comprising a revoluble, inclined tube, a helix in said tube, three or more supports for said tube, a strut ring intermediate between every two supports, a pair of conical plates united with said tube and at their apex and forming said 15 strut-ring, and a series of longitudinal stiffening trusses comprising oppositely inclined tension rods connected with said tube adjacent to each support and extending between adjacent supports and connected with the 20 intermediate strut ring.

11. A hollow screw elevator comprising a revoluble inclined tube, a helix and an axle within said tube and fastening means adapted to strain the axle against the helix and the helix against the tube and to permit the 25 removal of the helix and axle.

12. A hollow screw elevator comprising a revoluble inclined tube, a helical flange on the inside of said tube, a helix, an axle, a

thread on said axle, and a nut on said thread 30 abutting against a part of said tube and adapted to draw the helix into engagement with said flange on the tube and to permit the removal as a unit of said helix and axle.

13. A hollow screw elevator adapted to 35 be set with its axis inclined at a predetermined angle and comprising a revoluble inclined tube, a helix in and attached to said tube and radially inclined thereto at an obtuse angle which exceeds the obtuse setting angle of the elevator with the horizontal and combined therewith a gearing adapted to rotate the tube and prevent it from turning backward.

14. A hollow screw elevator adapted to 40 be set with its axis inclined at a predetermined angle and comprising a revoluble inclined tube, a helix in and attached to said tube, and radially inclined thereto at an obtuse angle which exceeds the obtuse setting angle of the elevator with the horizontal, and a frame, and combined therewith a 45 worm gear on the tube, and a worm revolvably mounted on the frame.
